SCYTHE SNATH WEB

Ernest N. Birge, Seymour, Ind., assigner to Seymour Manufacturing Company, Inc., Seymour, Ind., a corporation of Delaware

Application March 22, 1937, Serial No. 132,195

3 Claims. (Cl. 306—1.3)

This invention relates to means for securing a scythe blade to a snath, and one of its objects is to provide a fitting for this purpose adapted to be economically formed of sheet metal. Another object is to provide such a fitting designed for adjustment so that it can be applied to snaths of slightly different dimensions instead of requiring them to be finished to an exact size to receive the fitting. The invention consists in certain features and elements of construction in combination, as herein shown and described and as indicated by the claims.

In the drawing:

Figure 1 is a side view of a scythe blade and a portion of the snath to which it is attached.

Figure 2 is a face or plan view of a fitting embodying this invention and a fragment of a snath to which it is applied, the tang of the scythe blade being indicated in broken outline.

Figure 3 is a side elevation of the parts shown in Figure 2, with certain details in section, and with the tang of the blade in full lines and partly in section.

Figure 4 is an end elevation of the structure shown in Figures 2 and 3.

Figure 5 is a perspective view of the parts constituting the fitting itself apart from the snath.

The usual scythe blade 1 is formed with a tang 2, by which it is ordinarily secured by some form of clamping means to the end portion of the stick or snath 3 which serves as a handle. To provide for removable securement of the blade so that it may be readily separated from the snath for sharpening, the snath 3 is customarily provided with a metallic fitting which includes the fastening means for holding the tang 2 of the blade. The present invention provides such a fitting in the form of stampings of sheet metal, which permits of economical construction and relatively light weight. As shown in the drawing, the snath is preferably made with a sloping flat face 4 in order to set the blade 1 at a slight angle to the direction of the axis of the snath; thus the end portion of the snath is of tapering thickness, although the surface opposite the flat inclined face 4 is substantially cylindrical and concentric about the main axis of the piece. Embracing this cylindrical surface 5 I provide a "web" which includes a lower section comprising curved band portions 6 and 7 spaced apart longitudinally, and connected by a bar 8 which may be of curved form transversely so as to fit snugly against the cylindrical surface 5. The bands 6 and 7 are formed with apertured lugs 9 and 10,

respectively, projecting laterally at both sides of the snath 3.

A second member of the fitting consists of a flat plate portion 11 with laterally adjacent curved portions 12 merging into a curved end portion 13 which serves as a clamping band to fit over the cylindrical portion of the snath 3. Lugs 14 extend from the curved portion 13 at both sides of the snath, and are provided with apertures registering with those of the lugs 9 so that the two parts may be connected by clamping bolts 15 connecting their respective lugs in pairs. The flat, inclined portion 11 merges with the curved side portions 12 near the opposite end of the fitting, said flat portion 11 overlying the inclined flat surface 4 of the snath to the extreme end of the latter. Near this end an upturned lug 16 at one side of the area 11 serves as a stop against which the heel of the tang 2 of the blade may rest when the blade is secured in operative position. This surface 11 is also provided with a plurality of apertures 17 in any one of which the down-turned terminal 18 of the tang 2 may be engaged, as indicated in Figure 2, for anchoring this portion of the tang. In order to secure the portion 11 permanently in position against the flat surface 4 a fastening screw 19 may extend through the metallic fitting into the wood of the snath near the end of the latter.

A third part of the fitting consists of a clamp yoke 20 preferably of arched formation, and formed with a depressed central rib portion 21 which serves to stiffen the member, and also bears directly upon the corners of the tang 2 when the latter is lodged upon the flat, inclined surface 11. This engagement is indicated in Figures 3 and 4, which also show the laterally-projecting, apertured lugs, 22, which are integral portions of the yoke 20 and whose apertures register with those of the lugs 10 so that two clamping bolts 23 may be inserted for drawing the yoke 20 firmly into engagement with the tang 2. This clamping action simultaneously draws the curved band 7 firmly into engagement with the curved undersurface of the snath 3.

As shown, the sides of the snath adjacent the flat surface 4 are beveled or cut away slightly at 24 to accommodate the curved end portions of the yoke 20 but it may be understood that this particular formation may vary, depending upon the position at which the lugs 10 and 22 are located, and also upon the particular shape of the yoke 20 which, if desired, can be made to fully clear the cylindrical form of the snath 3. It may also be understood that if the inclina-

tion of the tang 2 with respect to the axis of the snath is not desired, the bearing surface 11 may extend substantially parallel to the axis of the snath, overlying a corresponding flat area of the snath itself parallel to said axis. Such a modification would merely require an increase in the depth of the yoke member 20 or the location of the lugs 10 at a plane nearer to the flat tang-receiving surface.

10 It will be recognized that my "web", or fitting, as described, is one which can be readily and economically manufactured by well-understood stamping processes for forming sheet metal, and that it may be made relatively light in proportion to its strength; it will also be seen that by reason of some flexibility in the sheet metal parts and the range of accommodation provided by forming the lugs 9 and 14 without lugs 10 and 22, so that they are normally spaced apart, the fitting may be secured tightly onto snaths of somewhat different sizes. It will also be useful for application to old snaths if the original fittings have broken, or even if the snath itself has broken off near the end, or split, so that it must be shortened for further use; a comparatively amateur job of fitting of the wooden part will suffice if my sheet metal web is applied and adjusted to the wooden part by means of clamping bolts 15 and 23. The use of a standard tang 2 may result 20 in the projection of its terminal 18 clear through the thickness of the flat portion 11 of the fitting, but in that event it is a simple matter to notch the snath as indicated at 4^a in Figure 3 to provide proper clearance. It will be recognized that 30 the employment of the bolts 23 for clamping the band portion 7 to the snath, and at the same time clamping the scythe tang 2 onto the surface 11, involves an economy of parts, and simplifies the structure.

40 While there is shown and described herein certain specific structure embodying the invention, it will be manifest to those skilled in the art that various modifications and rearrangements of the parts may be made without departing from the spirit and scope of the invention, and that the same is not limited to the particular form herein shown and described, except in so far as indicated by the appended claims.

I claim:

50 1. A fitting for fastening a scythe blade to a snath, comprising a pair of metallic bands each formed to partially encircle the snath in longitudinally spaced relation thereon with an integral tie connecting them, said bands terminating in outwardly projecting apertured lugs, a plate member 55 formed to overlie the snath at the side opposite the bands and including a curved end por-

tion terminating in outwardly projecting lugs having apertures disposed to register with the apertures of one of said bands, threaded means adjustably connecting said apertured lugs of the plate member to those of the band for adjustably clamping the snath between said parts, said plate member affording a flat surface for lodgment of the tang of a scythe blade, a yoke dimensioned to overlie the plate with such tang interposed, said yoke terminating in outwardly projecting lugs 10 having apertures disposed to register with those of the lugs of the other band, and threaded means adjustably connecting the apertured lugs of the yoke directly to those of said other band for clamping the tang against the plate and gripping 15 the snath.

2. A fitting for fastening a scythe blade to a snath, comprising a pair of metallic bands each formed to partially encircle the snath in longitudinally spaced relation thereon with an integral tie portion connecting them and curved concentrically with said bands to fit snugly against the curved surface of the snath, the opposite side of the snath having a flat surface inclined to the axis of the snath, a plate member 25 having a flat portion formed to fit over said flat surface of the snath and including a curved end portion to fit the snath beyond its flattened surface, means adjustably connecting said curved end portion and one of the said bands with the 30 snath embraced and clamped between them, said plate member affording a flat inclined surface for lodgment of the tang of a scythe blade, a yoke dimensioned to overlie said plate and a tang lodged thereon, and means adjustably connecting 35 said yoke directly to the other band for clamping the tang against the plate and gripping the snath.

3. A fitting for fastening a scythe blade to a snath comprising a pair of bands each formed to 40 partially encircle the snath in longitudinally spaced relation thereon with a tie rigidly connecting them, a plate member formed to overlie the snath at the side opposite said bands and including an end portion disposed adjacent one of 45 the bands, means adjustably connecting said end portion and said band with the snath embraced and clamped between them, said plate member affording a flat surface for lodgment of the tang of a scythe blade, a yoke dimensioned to overlie 50 the plate with such tang interposed, and means connecting said yoke directly to the other of the two bands and adjustable for clamping the tang against the plate and gripping the snath between 55 said yoke and the connected band.

ERNEST N. BIRGE.
